UNITED STATES PATENT OFFICE.

DIION KEEFE, OF WALLA WALLA, WASHINGTON.

FLOOR-FASTENING.

1,117,397.

Specification of Letters Patent.

Patented Nov. 17, 1914.

Application filed January 29, 1914. Serial No 815,187.

To all whom it may concern:

Be it known that I, DIION KEEFE, a citizen of the United States, residing at Walla Walla, in the county of Walla Walla and State of Washington, have invented certain new and useful Improvements in Floor-Fastenings, of which the following is a specification.

The fastening which is the subject matter of the present application for patent is designed for securing the floor timbers or planks of bridges, docks or similar structures.

It is the object of the invention to provide a fastening which facilitates the laying and securing in place of the flooring, and which permits the ready removal of single planks for the purpose of renewal, without rendering the fastening means unfit for further use.

The invention also has for its object to provide a fastening which is located on the under side of the planks, so that there is no chance of water getting around the same to rot the planks.

In the accompanying drawing forming a part of this specification, Figure 1 is a plan view of a fragment of a bridge, dock or similar structure provided with the floor fastening which is the subject matter of the present application for patent; Fig. 2 is a cross-section on the line 2-2 of Fig. 1; Fig. 3 is a plan view of the under side of the structure, and Figs. 4, 5 and 6 are elevations of the fastening units.

Referring specifically to the drawing, 10 denotes a superstructure composed of I-beams, on which are laid stringers 11, which latter are also I-beams. The floor planks 12 are laid on the stringers and secured thereto by the fastening devices to be hereinafter described. At the edges of the flooring are the usual guard beams 13.

The fastening means for each plank 12 comprises three units, to wit—a series of clips in the shape of a hook 14 having a threaded shank 15; a pin 16 having a threaded portion 17, and a lock comprising a hook 18 having a threaded shank 19 and 50 an offset extremity 20.

In laying the planks 12, a pin and a lock are screwed into the under side of each plank, near one end thereof, so as to come on opposite sides of the stringer 11 at the 55 corresponding end of the structure, and the clips are screwed into the under side of the

plank to come on one side of the remaining stringers. The clips are positioned so that the hooks 14 all point in one direction, in order that they may be slipped under the top flanges of the stringers on one side thereof. The pin 16 is positioned to engage the top flange of the end stringer on the inner side thereof, and the lock is positioned so that its offset hook portion 20 may be swung under the top flange of the end stringer on the outer side thereof. After the fastening devices are properly positioned as stated, the plank is laid on the stringers and driven lengthwise to engage the hooks with the stringer flanges, the lock first being turned away from the end stringer in order to permit the plank to be driven as stated. The lock is then turned to engage the hook portion 20 with the end stringer flange, which locks the plank fast and solid. The hook portion 18 of the lock engages the under side of the plank. The next plank is laid with the fastening devices reversed, so that the whole forms a brace to the stringers from both sides, thus holding the same very rigid. As the fastening devices are all on the under side of the planks, there is no chance for water to get around the same to rot the planks.

If a plank gets worn or injured, necessitating renewal, it can be easily removed by raising the guard beam 13 and reaching around the end plank, and turning the lock out of engagement with the end stringer flange. The plank is then driven in a direction to disengage the hooks 14 from the stringer flanges, after which the plank may be taken up. The fastening devices can be removed and placed on the new plank, which latter is secured as hereinbefore described, after which the guard beam is replaced. It will thus be seen that the flooring can be readily repaired with a great saving in time, labor and expense.

I claim:

1. The combination with a flooring composed of independent members, and stringers on which said members are laid and from which they are separately removable; of means for securing the flooring members to the stringers, said means comprising hook-shaped clips mounted on the under side of the flooring members to engage one side of all the stringers except one of the end stringers, and a locking device carried by the flooring members at one end thereof

and engaging the side of the aforesaid end stringer, and being disengageable from said end stringer, the clips all pointing in one direction to permit removal of the flooring members individually from the stringers by shifting said members in the direction of their length when the locking devices are disengaged from the end stringer.

2. The combination with a flooring composed of independent members, and stringers on which said members are laid and from which they are separately removable; of means for securing the flooring members to the stringers, said means comprising hook-shaped clips and a locking device mounted on the under side of each flooring member, the hooks of the clips all pointing in one direction to engage one side of the stringers, and the locking device engaging the opposite side of an end stringer and being disengageable therefrom, said locking device having a hook which engages the under side of the flooring member and has an offset stringer-engaging portion which points in the opposite direction from the hooks of the clips.

3. The combination with a flooring com-

posed of independent members and stringers on which said members are laid and from which they are separately removable; of means for securing the flooring members to the stringers, said means comprising hook-shaped clips and a locking device mounted on the under side of each flooring member, the hooks of the clips all pointing in one direction to engage one side of the stringers, and the locking device engaging the opposite side of an end stringer and being disengageable therefrom, said locking device having a hook which engages the under side of the flooring member and has an offset stringer-engaging portion which points in the opposite direction from the hooks of the clips.

In testimony whereof I affix my signature in presence of two witnesses.

DION KEEFE.
